UNITED STATES PATENT OFFICE.

CHARLES J. HAUSEN, OF NEW YORK, N. Y.

HOSE-SUPPORTER.

1,216,991.

Specification of Letters Patent. Patented Feb. 20, 1917.

Application filed March 2, 1916. Serial No. 81,658.

To all whom it may concern:

Be it known that I, CHARLES J. HAUSEN, a citizen of the United States, and a resident of the city of New York, borough of 5 Manhattan, in the county and State of New York, have invented a new and Improved Hose-Supporter, of which the following is a full, clear, and exact description.

The object of the invention is to provide 10 a new and improved hose supporter arranged to insure perfect freedom of the wearer's body and limbs without producing undue strains on the hose and thus preventing tearing the same.

15 In order to accomplish the desired result, use is made of a flexible supporting member, preferably in the form of an elastic band, attached at its ends to the front and rear of the corset or similar garment, a loop attached to the garment intermediate the attachment of the band ends, the said bands slidingly engaging said loop to form two depending V-shaped portions, and hose 20 clasps provided with pivoted loops slidingly engaging the said depending band portions at the apexes thereof.

A practical embodiment of the invention is represented in the accompanying drawings forming a part of this specification, in 30 which similar characters of reference indicate corresponding parts in all the views.

Figure 1 is a perspective view of the hose supporter as applied;

35 Fig. 2 is a similar view of the same with the parts in position when the wearer is walking;

Fig. 3 is a rear perspective view of the same as applied;

40 Fig. 4 is an enlarged face view of a portion of the middle of the band slidingly engaging a loop;

Fig. 5 is a front elevation of one of the 45 hose clasps and its connection with the supporting band; and

Fig. 6 is a cross section of the same on the line 6—6 of Fig. 5.

The supporting member of the hose supporter is preferably in the form of an elastic band 9 having its rear end formed into an eye 10 engaging a segmental loop 11 fastened by stitches or other fastening means 12 to the corset or other garment 13 at the rear thereof. The forward end of 55 the band 9 is provided with a lengthening and shortening buckle 14 of usual construction

to form an eye 15 engaging a segmental loop 16 fastened by stitches or other fastening means 17 to the garment 13 at the front thereof. A segmental loop 18 is attached 60 by stitches or other fastening means 19 to the garment 13 intermediate the loops 11 and 16, that is, over the corresponding hip portion of the garment 13. This intermediate loop 18 is slidably engaged by the 65 middle portion 20 of the band 9 and by reference to the drawings it will be noticed that the loops 11 and 16 are inclined toward each other, that is, the loop 11 is inclined forwardly and upwardly and the loop 70 16 is inclined downwardly and rearwardly. The loop 18 is inclined downwardly and forwardly so that the band portion 20 freely slides in this loop on the wearer moving the 75 limbs and body while walking and exercising. It will be noticed that by connecting the band 9 with the loops 11, 16 and 18 in the manner described, the band 9 is formed into two depending V-shaped portions 21 and 22, each slidably engaging a segmental 80 loop 23 of a hose clasp 24 for connection with the hose 25 to be supported.

Each of the hose clasps 24 is preferably of the construction more fully shown and described in the applications for Letters 85 Patent of the United States, No. 833,691 and No. 2,141, filed by me April 22, 1914, and January 14, 1915, respectively.

Each hose clasp 24 consists of a plate 26 90 having a sidewise extending slot 27 adapted to be engaged by a button 28 for clamping the hose material in position on the plate 26. The button 28 is attached to a tape 29 secured at its upper end to an eye 30 95 formed on the top of the plate 26. The loop 23 has its ends pivotally connected with the plate 26 intermediate the slot 27 and the eye 30 so that the loop 23 has a free swinging movement and the hose portion 21 100 or 22 has a free sliding movement on the segmental loop 23. The eyes in which the ends of loop 23 are pivoted are of sufficient size to permit the swinging movement of the loop.

105 It will be noticed that by the arrangement described, the band 9 is free to slide through the loops 18 and 23 and is free to slide on the loops 11 and 16 so that the band 9 readily adapts itself to the movement of the 110 wearer's body and limbs without producing an undue strain on the hose clasps and con-

sequently on the hose, thereby preventing tearing of the latter. It is understood that the loop 18 is inclined downwardly and forwardly owing to the movement of the body 5 relatively to the limbs, that is, the body and limbs assume a forward angular position in walking or exercising, and consequently the middle portion 20 of the band 9 freely slides in this loop and travels along 10 the loop 18 without danger of binding. A similar traveling action of the ends of the band 19 takes place in the loops 11 and 16 owing to their particular inclination in the manner above set forth.

15 Having thus described my invention, I claim as new and desire to secure by Letters Patent:

1. A hose supporter comprising a flexible supporting member, obliquely disposed 20 means for movably attaching the ends of said member to a corset or like garment at the front and rear of the garment, a loop flexibly secured to the garment at its hips in an oblique position and slidably engaged 25 by the said supporting member to form front and rear depending portions, clasps adapted to engage the hose, loops pivotally mounted on said clasps and slidably engaging said depending portions of the flexible 30 supporting members.

2. A hose supporter comprising a flexible supporting web, means for movably attaching the front and rear ends of the same to a corset or like garment at the front and 35 rear of the garment, a segmental loop flexibly secured to the garment at the hips in an oblique position and slidably engaged by the said supporting member to form front and rear depending portions, and clasps adapted to engage the hose, said clasps having a segmental loop provided with rounded sides and pivotally secured to the clasps, said loops slidably engaging said depending portions of the flexible supporting member.

45 3. A hose supporter comprising a flexible supporting member including front and rear angular pendent portions, and a clasp for engaging the hose and slidably engaging the pendent portions at their apices said clasps 50 including a segmental open loop pivotally

secured to the clasp and having rounded sides.

4. A hose supporter comprising an elastic band and a corset or like garment, separate means for movably attaching the ends of the 55 band to the corset or like garment at the front and rear of the corset, said attaching means being secured to the corset or like garment at points adjacent a vertical plane defining the vertical median line of the garment, said attaching means being oppositely inclined to permit the band to converge downwardly and lie smooth in converging position and allow the band to slide easily, a segmental loop attached to the garment at 60 the hip portion and inclined forwardly and upwardly the middle portion of said band slidably engaging said hip loop and forming two pendent V-shaped portions, and 65 clasps adapted to engage the hose and having a sliding connection with the said pendent band portions at the apices thereof.

5. A hose supporter comprising an elastic band for attachment to a corset or like garment, separate means for movably attaching 70 the ends of the band to the garment at its front and rear, said means flexibly attached to the front and rear of the garment at points adjacent a vertical plane defining the vertical median line of the garment and consisting of a pair of oppositely inclined segmental loops whereby the end portions of 75 the band are permitted to converge downwardly and lie smooth in converging position, a segmental loop flexibly connected to 80 the garment at its hip portion and substantially midway between the front and rear segmental loops, said hip loop being inclined forwardly and upwardly and receiving and guiding the band to form front and 85 rear pendent V-shaped members, and clasps slidably carried at the apices of the V-shaped members.

In testimony whereof I have signed my name to this specification in the presence of 95 two subscribing witnesses.

CHARLES J. HAUSEN.
